WAVE GUIDE SWITCH

Morris Moses Robison and Lawrence L. Lodge, Columbus, Ohio; said Robison assignor to Thompson Products, Inc., Cleveland, Ohio, a corporation of Ohio

Application July 28, 1954, Serial No. 480,818

(Filed under Rule 47(a) and 35 U. S. C. 116)

3 Claims. (Cl. 333—98)

The invention relates to a wave guide switch and more particularly to an efficient, reliable and simply and economically constructed wave guide switch by which one wave guide for the transmission of ultra-high frequency electromagnetic energy may be selectively conducted to one of two or more other wave guides with a minimum of energy loss and with a minimum of discontinuity between the guides.

In the wave guide switch of this invention, a housing defines a pair of facing divergently related surfaces and a switch element is selectively movable between positions respectively cooperating with such divergently related surfaces to define alternative wave transmission paths. To simplify construction, the switch element may preferably have one surface portion cooperating with one of the divergent surfaces to define one transmission path in one position of the element and another surface portion cooperating with the other of the divergent surfaces to define an alternative transmission path. Most preferably, such other surface portion of the switch element forms a smooth continuation of such one of the divergent surfaces in the one position of the element and such one surface portion of the element similarly forms a smooth continuation of such other of the divergent surfaces of the housing in the other position of the switch element.

According to a specific feature of the invention, the surface portions of the switch element are converged to a sharp edge selectively engageable with opposed portions of divergent surfaces of the housing so as to achieve a smooth transition. Most preferably, the edge may be slightly resilient so as to obtain good electrical contact.

The direction of transmission of energy must, of course, be changed in at least one of the alternative wave transmission paths. According to a further feature of the invention, at least one of the divergent surfaces of the housing is convexly curved and the cooperating surface portion of the switch element is concavely curved in complementary relation so as to introduce minimum discontinuity in the transmission of energy over a wide range of frequencies. Preferably, both of the divergent surfaces of the housing are convexly curved and both convergent surfaces of the switch elements are concavely curved so as to provide a symmetrical construction.

According to still another feature of the invention, the switch element is movable rectilinearly. Preferably, the divergently related surfaces of the housing are divergent from first portions in closely spaced facing relation to second portions spaced a greater distance apart and the housing also defines a pair of surface portions in closely spaced relation to such second portions of the divergent surfaces and a plane surface portion between such pair of surface portions. The switch element has a plane surface portion slidable over the plane surface portion of the housing and has a pair of surface portions respectively arranged to form smooth continuations of the pair of surface portions of the housing as the element is moved between first and second positions. The plane surface portion of the housing may form a continuation of

2

at least one, and preferably both, of the surface portions of the housing that are disposed in spaced facing relation to the spaced apart portions of the divergent surfaces above referred to. In this case, the divergent surfaces of the housing may extend in an arc of 90°.

According to a specific feature of the invention, the plane surface of the rectilinearly movable switch element may be resiliently urged into pressure engagement with the plane surface of the housing so as to achieve good electrical contact.

Still another feature of the invention is in the provision of actuating means for the switch element arranged for resiliently urging the element into either of its two alternative positions. The provision of such actuating means is particularly advantageous in the case wherein the surface portions of the switch element are converged to the resilient edge selectively engageable with the facing divergent surfaces of the housing.

According to a further specific feature of the invention, such actuating means may comprise an actuating lever having a slot therein with a pin resiliently carried by a shaft and extending into the slot, means being provided for rotating the shaft for resiliently urging the lever selectively into either of its two operative positions. The resilient support of the pin may preferably comprise a wheel having a recessed end face defining a radially inwardly facing cylindrical wall with an arm pivoted within such recess carrying the pin and with compression spring means acting on the arm to move the arm against the wall while allowing radially inward deflection of the pin. The pin may be movable between positions on opposite sides of a line through the pivot axis of the lever and the axis of the shaft or wheel to position the lever in either of its two operative positions.

With this arrangement, the behavior of the actuator mechanism is rendered uncrucial because of the take-up provided by the resiliently supported pin.

An object of this invention, accordingly, is to provide an improved wave guide switch.

Another object of this invention is to provide an improved wave guide switch including a housing defining a pair of facing divergently related surfaces with a switch element selectively movable between positions respectively cooperating with such surfaces to define alternative wave transmission paths.

A further object of this invention is to provide a wave guide switch including a switch element having oppositely facing surfaces converged to an edge.

Still another object of this invention is to provide an improved wave guide switch including convexly and concavely curved cooperating surfaces to minimize discontinuities.

A still further object of this invention is to provide an improved wave guide switch including a rectilinearly movable switch element.

Yet another object of this invention is to provide an improved wave guide switch including a rectilinearly movable switch element having a plane surface resiliently urged against and slidable over a plane surface portion of a housing of the switch.

Still another object of the invention is to provide improved actuating mechanism for a wave guide switch or the like.

This invention contemplates other and more specific objects, features and advantages which will become more fully apparent from the following detailed description taken in conjunction with the accompanying drawing which illustrates a preferred embodiment and in which:

Figure 1 is a top plan view of a wave guide switch constructed in accordance with the principles of the present invention; and

Figure 2 is a sectional view taken substantially along line II—II of Figure 1.

Reference numeral 10 generally designates a wave guide switch constructed according to the principles of this invention. The switch 10 may comprise a housing including a main body portion 11 and cover flanges 12, 13 and 14 secured to the body portion 11 and providing means for connecting the switch to wave guides. A wave guide connected to the cover flange 14 may be selectively connected to wave guides connected to the cover flanges 12 and 13 through the structure of the wave guide switch 10 of this invention.

The switch housing defines internal surfaces generally designated by reference numerals 15 and 16 which may be divergent from portions 17 and 18 in closely spaced parallel relation to portions 19 and 20 spaced apart a considerable distance. In accordance with the features of this invention, at least one and preferably both of the divergent surfaces 15 and 16 are convexly curved and extend in an arc of 90° so that the portions 19 and 20 may be in the same plane.

A switch element 21 has oppositely facing surface portions 22 and 23. In the position of the element 21 illustrated, the surface portion 23 thereof cooperates with the divergent surface 16 of the switch housing to define one wave transmission path. The switch element 21 is movable to an alternative position in which the surface portion 22 thereof cooperates with the surface 15 of the switch housing to define an alternative wave transmission path. In accordance with the features of this invention, as discussed heretofore, the surface portions 22 and 23 may be concavely curved and may each extend in an arc of approximately 90°. In the position of the switch element 21 illustrated, the surface 23 preferably forms a smooth continuation of the portion 17 of the surface 15 while in the alternative position of the switch element 21, the surface portion 22 thereof forms a smooth continuation of the portion 18 of the surface 16. For this purpose, the surfaces 22 and 23 of the switch element 21 may be converged to a sharp edge 24 selectively engageable with the surfaces 15 and 16 adjacent the portions 17 and 18 thereof. According to a specific feature of the invention, the edge portion 24 is resiliently deflectable so as to insure good electrical contact. This may preferably be achieved by grinding the switch element 21 to a sharp edge. The portions of the surfaces 15 and 16 engaged by the element 21 adjacent the edge 24 may preferably be ground flat so as to insure good electrical contact.

The switch housing may define surface portions 25 and 26 in spaced facing relation to the portions 19 and 20 of the divergent surfaces 15 and 16 and a plane surface 27 between the surface portions 25 and 26. The switch element 21 may have a plane surface 28 in slidable engagement with the plane surface 27 of the housing, the switch element 21 being movable between a position as illustrated in which the surface portion 23 forms a smooth continuation of the surface portion 26 and an alternative position in which the surface portion 22 of the element forms a smooth continuation of the surface portion 25 of the housing. Most preferably, the surface portions 25, 26 and 27 of the housing are located in the same plane.

In the construction of the switch 10, the surfaces 27 and 28 are preferably very accurately ground plane so as to insure good electrical contact between the switch element 21 and the housing and so as to thereby minimize any discontinuity in the wave transmission paths.

In accordance with a specific feature of the invention, the surface 28 of the switch element is resiliently engaged with the plane surface 27 of the switch housing. For this purpose, a stud bolt member 29 may be threaded or otherwise secured to the switch element 21 and may project outwardly through a slot 30 into a recess 31 formed in the upper face of the housing. A leaf spring

element 32 may have a central aperture receiving the bolt 29 and legs 33 and 34 in resilient sliding engagement with the outwardly facing surface of the recess 31. To transmit the upwardly directed force of the spring 32 to the bolt 29 and the switch element 21, a pair of nuts 35 and 36 are threaded on the bolt 29 above the leaf spring element 32, the position of the nuts 35 and 36 being adjustable to control the upward pressure exerted on the bolt 29 and the switch element 21.

It should be noted that the transmission paths may preferably be of generally rectangular cross-section and for this purpose the housing defined by the body portion 11 and the cover flanges 12, 13 and 14 may define facing surfaces 37 and 38 in spaced parallel planes transverse to the surfaces 15, 16, 22, 23. The surfaces 37 and 38 may be referred to as top and bottom internal surfaces but it will be understood that the switch may be disposed in any desired position.

By way of illustrative example, the spacing between the surfaces 37 and 38 may be 1½ inches and the spacing between the surfaces 17 and 18 may be ¾ inch which, of course, is equal to the spacing between surface portions 19, 25, surface portions 20, 26, surfaces 16, 23 in the position of switch element 21 illustrated, or between 15 and 22 in the alternative position of the switch element 21. With these dimensions and with a proportionate radius of bend of the paths as illustrated, the switch 10 is operable over a frequency range of 5,850 to 8,200 megacycles with a voltage standing wave ratio of less than 1.05.

To actuate the switch element 21, an actuating mechanism generally designated by reference numeral 39 is mounted on a support flange 40 affixed to one side of the main body portion 11 of the switch housing. The actuating mechanism 39 includes a lever 41 having one end 42 projecting into a slot 43 in the main body portion 11 of the switch housing, the lever 41 being pivoted within the slot 43 on a vertically extending screw 44. The end 42 of the lever 41 has a bifurcated end portion receiving the stud bolt 29 to effect rectilinear movement of the switch element 21 between its alternative positions with movement of the lever 41 about the axis of the screw 44.

The other end of the lever 41 has a radially extending slot 45 receiving a pin 46 which is carried from a shaft 47 through a wheel 48. An electric actuating motor 48a (the lower end of which appears in Figure 2) is mounted on the under side of the support flange 40 and is arranged to rotate the shaft 47 either clockwise or counter-clockwise so as to rotate the lever 41 counter-clockwise through the pin 46 and shift the switch element 21 to its alternative position. The actuating motor 48 may then be again energized to rotate the shaft 47 back to position illustrated.

To control stopping of the actuating motor 48, a pair of micro-switches 49 and 50 are mounted on the support flange 40 on opposite sides of the wheel 48 and have actuating arms 51 and 52, respectively, which support rollers 53 and 54, respectively, arranged to be engaged by a cam member 55 projecting from the periphery of the wheel 48.

A further feature of the actuating mechanism 39 is in the support of the pin 46 from the shaft 47. According to this feature, the wheel 48 may have a recessed upper end face defining a radially inwardly facing cylindrical wall 56. The pin 46 is affixed to an arm 57 which is supported within such recess by means of a pin 58. The arm 57 is urged into engagement with the wall 56 by means of a helical compression spring 59 acting between the end of the arm 57 and a bracket 60 secured within the recess in the end face of the wheel 48. With this arrangement, the pin 46 is urged radially outwardly and is movable radially inwardly toward the axis of the shaft 47 against the force of the spring 59. As heretofore pointed out, this resilient support of the pin 46 is

highly advantageous because the behavior of the actuating mechanism 39 is rendered uncritical and the wheel 48 need not be accurately stopped, but reasonable amounts of overshoot may be tolerated.

It will accordingly be apparent that this invention provides an efficient, reliable and simply and economically manufacturable wave guide switch by which one wave guide may be selectively connected to either of two other wave guides with a minimum of energy loss and with a minimum of discontinuity between the guides.

It will be understood that modifications and variations may be effected without departing from the spirit and scope of the novel concepts of this invention.

What is claimed is:

1. In a wave guide switch, a housing including first and second aligned rectangular openings having side walls lying in common planes and a third rectangular opening having side walls lying in planes transverse to said common planes, said housing having a pair of convexly curved internal surfaces extending symmetrically from said side walls of said third opening to side walls of said first and second openings and having a planar internal surface interconnecting the other side walls of said first and second openings, and a switch element slidably engaged with and shiftable in a direction parallel to said planar surface and having a pair of concavely curved external surfaces converged from a pair of edge portions adjacent said planar surface to a sharp edge portion located between and selectively engageable with said side walls of said third opening, said housing having top and bottom internal planar surfaces interconnecting said side walls of said openings, said convexly and concavely curved surfaces being in facing relation to define wave transmission paths between said third opening and said first and second openings, the curvatures of and spacings between said convexly and concavely curved surfaces being such as to provide a smooth transmission of high frequency energy through said paths and between said third opening and said first and second openings in the extreme positions of shiftable movement of said switch element.

2. In a wave guide switch, a housing including first and second aligned rectangular openings having side walls lying in common planes and a third rectangular opening having side walls lying in planes transverse to said common planes, said housing having a pair of convexly curved internal surfaces extending symmetrically from said side walls of said third opening to side walls of said first and second openings and having a planar internal surface interconnecting the other side walls of said first and second openings, a switch element slidably engaged with and shiftable in a direction parallel to said planar surface and having a pair of concavely curved external surfaces converged from a pair of edge portions adjacent said planar surface to a sharp edge portion located between and selectively engageable with said side walls of said third opening, said housing having top and bottom internal planar surfaces interconnecting said side walls of said openings, said convexly and concavely curved surfaces being in facing relation to define wave transmission paths between said third opening and said first and sec-

ond openings, the curvatures of and spacings between said convexly and concavely curved surfaces being such as to provide a smooth transmission of high frequency energy through said paths and between said third opening and said first and second openings in the extreme positions of shiftable movement of said switch element, and actuating means for shifting said switch element between said extreme positions of movement, said actuating means including means for resiliently urging said sharp edge portion against either of said side walls of said third opening with a certain force to minimize cross-talk.

3. In a wave guide switch, a housing including first and second aligned rectangular openings having side walls lying in common planes and a third rectangular opening having side walls lying in planes transverse to said common planes, said housing having a pair of convexly curved internal surfaces extending symmetrically from said side walls of said third opening to side walls of said first and second openings and having a planar internal surface interconnecting the other side walls of said first and second openings, a switch element slidably engaged with and shiftable in a direction parallel to said planar surface and having a pair of concavely curved external surfaces converged from a pair of edge portions adjacent said planar surface to a sharp edge portion located between and selectively engageable with said side walls of said third opening, said housing having top and bottom internal planar surfaces interconnecting said side walls of said openings, said convexly and concavely curved surfaces being in facing relation to define wave transmission paths between said third opening and said first and second openings, the curvatures of and spacings between said convexly and concavely curved surfaces being such as to provide a smooth transmission of high frequency energy through said paths and between said third opening and said first and second openings in the extreme positions of shiftable movement of said switch element, a pivoted actuating lever connected to said switch element and having a radially extending slot, a pin in said slot, a shaft carrying said pin and rotatable for selectively positioning said pin on opposite sides of a line through the pivot axis of said lever and the axis of said shaft for positioning said lever in either of two operative positions and moving said switch element into either of said extreme positions, and resilient means urging said pin radially outwardly to resiliently urge said lever into either of said operative positions.
